CLAIM

The ornamental design for a gaming machine, as shown and described.

DESCRIPTION

This application also incorporates by reference the following applications in their entirety: U.S. patent application Ser. No. 29/774,758, filed Mar. 18, 2020. All disclosure and subject matter, including all figures, of these applications are specifically incorporated by reference in this application as if set forth fully herein.

FIG. 1 is a front perspective view of a gaming machine showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a rear perspective view thereof;

FIG. 9 is another front perspective view thereof, showing our new design in an illuminated state;

FIG. 10 is an enlarged view of the portion 10 encircled in FIG. 1;

FIG. 11 is an enlarged view of the portion 11 encircled in FIG. 1;

FIG. 12 is an enlarged view of the portion 12 encircled in FIG. 1;

FIG. 13 is an enlarged partial perspective view thereof, showing the leaf portion separately for clarity of illustration; and,

FIG. 14 is an enlarged partial top plan view thereof, showing the leaf portion separately for clarity of illustration.

The dashed broken lines in the drawings illustrate portions of the gaming machine that form no part of the claimed design. The dot-dash broken lines in the drawings encircle portions of the claimed design that are illustrated in enlargements and form no part of the claimed design. The lines emitting from the screen frame of the gaming machine, in FIG. 9, illustrate the appearance of illumination and form no part of the claimed design.
